IMMERSION ROLL ASSEMBLY FOR SIZING
BOXES

John Henry Franks, Whitmire, S. C.

Application April 20, 1934, Serial No. 721,601

2 Claims. (Cl. 28—28)

This invention has reference to the art of sizing warp yarn and the object of the invention is to provide an improved immersion roller assembly for use with the sizing box to the end that whereas formerly two sizing operations were substantially resorted to, through the medium of the present invention but a single sizing box and a single sizing operation may be required while at the same time more efficient sizing of the yarn is obtainable.

The invention together with its objects and advantages will be best understood from a study of the following description taken in connection with the accompanying drawings wherein:

Figure 1 is a view partly in section and partly in elevation illustrating the application of the invention.

Figure 2 is a fragmentary plan view with certain parts shown in section.

Figure 3 is a fragmentary vertical sectional view showing the mechanism for raising and lowering the roller assembly.

Figure 4 is a sectional view through the roller assembly.

Figure 5 is an elevational view of the roller assembly, and

Figure 6 is a fragmentary sectional view showing the manner of connecting the side members of the frame forming part of the roller assembly.

Referring to the drawings by reference numerals it will be seen that 5 indicates the yarn to be sized, 6 the beams from which the yarn is fed to the sizing box 7, while 8 indicates the roller usually provided at the inlet end of the box 7 and over which the yarn 5 is trained, while 9 indicates generally the first pair of squeeze rolls, and 10 the second pair of squeeze rollers. The above is conventional and is not of the essence of the present invention.

In accordance with the present invention there is provided an improved immersion roll assembly indicated generally by the reference numeral 11. The assembly 11 comprises a frame structure consisting of a pair of identical substantially inverted U-shaped side members 12 the legs of which are connected by tie rods 13 respectively secured at their respective ends to the legs of the members 12 by pairs of inner and outer nuts 14 as clearly shown in Figures 5 and 6. Supported between the lower ends of the legs 12a of the side members 12 is an immersion roller 15 while a second immersion roller 16 is journalled and supported between the lower ends 55 of the legs 12b of the frame members 12.

The legs 12a, 12b of the side members 12 are adapted to extend into the solution 17 within the tank or box 7 and the legs 12a operate between pairs of suitable guides 18 secured to opposite side walls of the box 7 inwardly from the end wall of the box on which the roller 8 is supported as clearly shown in Figure 1.

Secured to and in line with the legs 12a are rack bars 19 and these bars may be secured to the ends of the legs 12a in any suitable manner as by being integral therewith or as otherwise found desirable.

The rack bars 19 are in constant mesh with pinion wheels 20 provided adjacent the ends of a transverse shaft 21 that has the ends thereof suitably journalled in the side walls of the box or tank 7. On one end thereof the shaft 21 is equipped with a handle 22 and also with a ratchet wheel 23 with which is engageable a dog 24 pivotally mounted on a suitable bracket 25 arranged on the adjacent side wall of the box 7.

In actual practice and as is clearly shown in Figure 1 the device 11 is mounted so as to position the rollers 15 and 16 transversely of the box 7 with the legs 12a operating between the guides 18—18 and the rack bars 19 in mesh with the pinions 20. It will be further noted that the side members 12 of the frame 11 are spaced from but straddles the first pair of squeeze rollers 9 so that, as shown in Figure 1 the yarn 5 first passes under the first immersion roll 15, then between the first set of squeeze rolls 9, passing from between these rolls 9 under the second immersion roller 16, and from the roller 16 between the rollers 10 to pass from the box 7. In this connection it will be noted that in passing under the rollers 15 and 16 the fabric 5 passes through the solution 17, and by operating the hand wheel 22 the rollers 15, 16 may be placed at any desired depth. Also the device 11 may be readily raised to facilitate the initial training of the yarn 5 under the rollers 15 and 16.

From the above it will be apparent that through the medium of the roller assembly of this invention an immersion of the yarn 5 into the solution 17 is made prior to and also subsequent to the passage of the yarn 5 through the first set of squeeze rollers 9. Thus two immersion or dipping operations of the yarn 5 is accomplished without resort to the passing of the yarn through a sizing solution in a second sizing box as heretofore was necessary due to the fact that at the present time the practice has generally been to pass the yarn 5 directly from the rollers 9 to the rollers 10 with a result that after passing between the rollers 9—55.

there is no further immersion of the yarn until the yarn is fed to a second sizing box, whereas in accordance with the present invention a second immersion operation takes place, and this 5 second operation takes place during the passage of the yarn from the first set of rollers 9 to the second set of rollers 10 as before explained.

Having thus described my invention, what I 10 claim as new is:

1. In combination with a sizing box having side walls, an immersion roller assembly comprising a pair of inverted U-shaped members and tie rods connecting said members, guide means 15 mounted on the said side walls of the sizing box, and said side members having one leg thereof engaging said guide members whereby said side members are supported for vertical movement, immersion rollers supported between said side members at the lower ends of the legs of said 20

side members, and means for vertically adjusting said side members.

2. In combination with a sizing box having side walls, an immersion roller assembly comprising a pair of inverted U-shaped members and tie rods 5 connecting said members, guide means mounted on the said side walls of the sizing box, and said side members having one leg thereof engaging said guide members whereby said side members are supported for vertical movement, immersion 10 rollers supported between said side members at the lower ends of the legs of said side members, and means for vertically adjusting said side members, said means including a shaft extending transversely of the sizing box, pinions on said 15 shaft, and depending rack bars connected with one leg of said side members and meshing with said pinions, and handle means for the shaft for rotating it.

JOHN HENRY FRANKS. 20
